(57) **CLAIM**

The ornamental design of a looped wallet, as shown and described.

DESCRIPTION

FIG. 1 shows a front perspective view of applicant's design of a first embodiment of a looped wallet.

FIG. 2 shows a top plan view of applicant's design of the first embodiment of the looped wallet of FIG. 1.

FIG. 3 shows a bottom plan view of applicant's design of the first embodiment of the looped wallet of FIG. 1.

FIG. 4 shows a left end elevational view of applicant's design of the first embodiment of the looped wallet of FIG. 1.

FIG. 5 shows a right end elevational view of applicant's design of the first embodiment of the looped wallet of FIG. 1.

FIG. 6 shows a frontal elevational view of applicant's design of the first embodiment of the looped wallet of FIG. 1.

FIG. 7 shows a rear elevational view of applicant's design of the first embodiment of the looped wallet of FIG. 1.

FIG. 8 shows a front perspective view of applicant's design of a second embodiment of a looped wallet.

FIG. 9 shows a top plan view of applicant's design of the second embodiment of the looped wallet of FIG. 8.

FIG. 10 shows a bottom plan view of applicant's design of the second embodiment of the looped wallet of FIG. 8.

FIG. 11 shows a left end elevational view of applicant's design of the second embodiment of the looped wallet of FIG. 8.

FIG. 12 shows a right end elevational view of applicant's design of the second embodiment of the looped wallet of FIG. 8.

FIG. 13 shows a frontal elevational view of applicant's design of the second embodiment of the looped wallet of FIG. 8; and,

FIG. 14 shows a rear elevational view of applicant's design of the second embodiment of the looped wallet of FIG. 8. The features shown in broken lines form no part of the claimed design. The broken lines are for unclaimed environment or boundaries that form no part of the claimed design.

1 Claim, 4 Drawing Sheets
